(57) **CLAIM**

The ornamental design for a cattle oral distraction device, as shown and described.

DESCRIPTION

FIG. 1 is a front, top and left side perspective view of a cattle oral distraction device in accordance with the present design;

FIG. 2 is a perspective view of the design showing a rear, a bottom, and a right side of the design;

FIG. 3 is an elevational view of the left side of the design;

FIG. 4 is an elevational view of the right side of the design;

FIG. 5 is an elevational view of the rear of the design;

FIG. 6 is an elevational view of the front of the design;

FIG. 7 is a plan view of the top of the design; and,

FIG. 8 is a plan view of the bottom of the design.

The broken lines depict unclaimed subject matter for illustrative purposes only and form no part of the design claim.

1 Claim, 8 Drawing Sheets
